UNITED STATES PATENT OFFICE

JOHN H. HILPMAN, OF HOLLIS, NEW YORK, ASSIGNOR TO MERGENTHALER LINOTYPE COMPANY, A CORPORATION OF NEW YORK

SLUG CASTING MACHINE

Application filed May 5, 1931. Serial No. 535,118.

This invention relates to slug casting machines of the general organization represented in U. S. Letters Patent No. 436,532, to O. Mergenthaler, wherein a printing slug or type bar is cast in a slotted mold against an assembled line of matrices presented momentarily thereto, and wherein the slug after casting is removed from the mold by an ejector which advances from the rear and pushes it forwardly between a pair of trimming knives into a receiving galley at the front of the machine.

In these machines, the mold equipment is variable or adjustable as to the length of the mold slot, in order to produce slugs for printing columns or pages of different widths; and in connection with such adjustable mold equipment, there is frequently employed a composite ejector having its parts so constructed and combined that its operative portion may be varied in width to correspond with changes in the length of the mold slot. As illustrated for instance in Letters Patent of the United States, No. 967,976, to John R. Rogers, the ejector blade is composed of a series of parallel sections arranged edge to edge, and adjusting mechanism is provided whereby any desired number of these sections can be connected with the actuating slide, while the others are left free therefrom. This adjusting mechanism is actuated by a hand lever exposed at the front of the machine and which carries a locking detent to hold it in its set position.

In practice, it sometimes occurs that the locking detent is accidentally or unintentionally released and the hand lever displaced from its set position, with the result that the proper adjustment of the ejector blade is destroyed. Thus, in selecting a mold for slugs of a given length, say 30 ems, the ejector is set to the appropriate width, and if such setting is accidentally or inadvertently disturbed, either too many or too few of the blade sections will be brought into use and serious damage is bound to result. For example, if too many blades are in use, the ejector will be too wide to enter the mold slot and, as the blade sections are advanced in the ejecting operation, some of the blades

will strike against the back of the mold and be broken, or some other part of the machine damaged. On the other hand, if too few of the blade sections are in use, the slug will be ejected only partially (i. e., the lower end of the slug will be pushed forwardly out of the mold slot but the upper end will merely pivot and will remain therein), and hence, when the mold disc is revolved to bring the mold again into ejecting or casting position, the protruding portion of the slug will be broken off by contact with parts of the machine standing in its path, or will damage such parts, or both. In any case, and at best, recombination of the matrix line and recasting of the slug will be necessary.

To obviate the foregoing and other objectionable features, the present invention contemplates safety means whereby the ejector blade adjusting mechanism, when once set in any predetermined position, is automatically locked against accidental movement, readjustment, or mal-adjustment.

In the accompanying drawings the invention is shown merely by way of example and in preferred form, but obviously many changes and variations may be made therein which will still be comprised within its spirit. Therefore, it is to be understood that the invention is not limited to any specific form or embodiment, except insofar as such limitations are specified in the appended claims.

Referring to the drawings:

Fig. 1 is a detached view of the ejector and adjusting mechanism, with the present improvements embodied therein, and showing the mechanism adjusted to its lowest position;

Fig. 2 is a side view of the adjusting lever, showing by the full lines the parts in unlocked condition, and showing by the broken lines the parts resting in locked condition; and

Fig. 3 is a plan view showing the relation of the lever and holding detent to the toothed sector.

There are two general methods followed for casting type bars or slugs of different lengths, one involving the employment of a

so-called adjustable mold, i. e., one whose mold slot may be shortened or lengthened to the required extent, and the other involving the use of a plurality of interchangeable molds having casting slots of the different lengths desired. In the present instance, this latter method has been adopted for purposes of illustration. The several molds, only one of which is shown and which is marked 1 (see Fig. 1), are mounted upon a rotatable carrier or disc 2 which is adapted to transport the mold and contained slug from a horizontal casting position to the vertical position shown in Fig. 1, where it is located immediately in front of a composite ejector comprising a series of parallel blades or sections 3. The several ejector sections 3 are free to move forward and backward independently and are so arranged that any desired number may be brought into action conjointly to form an ejector of a width corresponding to the length of the slug to be cast, the unused sections remaining inactive or at rest in their backward position. The selection of the requisite number of ejector sections is effected by means of a vertically movable bar 6, which is connected to an ejector slide 4 actuated through a link 5 from the main shaft of the machine. In order that the bar 6 may move forwardly with the ejector slide 4, carrying before it those sections which it has connected to the ejector slide by its vertical adjustment, it is slidably mounted at its lower end on a horizontal rod 7, attached at one end to a vertical slide 8. The adjustment of the bar 6 to various heights for the selection of a greater or lesser number of the ejector sections is effected by means of a hand lever 9, pivotally mounted on a bracket 10, at 10^a, and connected at its rear end with the vertical slide 8. For convenience in operation, the forward end of the lever 9 is fashioned into a handle 9^a. Pivotally attached to the handle 9^a, at 12, is a latch handle 11 having a bracket 13, formed with a detent 14. This detent 14 is adapted to engage between the teeth 15 of a toothed sector 16 to maintain the lever 9 in its set position. To hold the detent 14 in locking position, a coil spring 17 is located between the lever handle and the latch handle, thereby tending to force the two apart, and is held in place by lugs 18 and 19 formed on the respective handles, and which project into opposite ends of the spring. The mechanism already described has been selected merely by way of example and to illustrate a preferred embodiment of the invention, such mechanism being well known and in use upon the commercial linotype machines. It should be understood, however, that the invention may be adapted to other forms of adjustable ejecting devices and to other constructions which present a different form of mechanism from that herein illustrated. As before stated, the present invention

is directed to an automatic safety device which will prevent an accidental or unintentional change of adjustment of the ejector mechanism.

The safety device, as herein illustrated, comprises a supplemental lock 20 which is arranged to be moved into and out of locking engagement with the latch handle 11, and for this purpose the end of the lever handle 9^a is bifurcated as at 22, and the lock is pivotally mounted on a pin 21 extending across said bifurcation so that it may be rocked forwardly and rearwardly. The upper portion of the lock 20 is thin and of arcuate shape, and to perform its locking function, it is formed at its upper end with a shoulder 26 which, when the lock is rocked rearwardly, is adapted to engage a projection 27 of the latch handle 11. At its lower end, or below the pivot 21, the lock 20 is formed with a flat grip portion 20^a extending rearwardly beneath the handle 9^a in parallel relation therewith. To hold the safety lock normally in active position, and to cause it to function automatically, a coil spring 23, seated in a recess 24 in the underside of the lever handle 9^a, presses downwardly against the grip portion 20^a, which latter has a projection 25 entering the lower end of the spring to hold it in place.

The operation of the parts will now be clear: To disengage the safety lock 20, in order that the holding detent 14 may be released and the hand lever 9 operated, the latch handle 11, the handle 9^a, and the grip portion 20^a are all grasped in the hand of the attendant, the upward pressure applied to the grip portion 20^a tilting the lock 20 forward at its upper end to disengage the locking shoulder 26 from the projection 27. The latch handle 11, now being released, it is next pressed downward toward the handle 9^a, to retract the detent 14 from engagement with the teeth 15 of the sector 16. The lever handle 9^a is then free to be moved upwardly or downwardly to lower or raise the rod 6, as the case may be, and thus decrease or increase the width of the ejector blade. When the lever handle has been set in the required position, the attendant's grip is released, and the latch handle 11 is forced upwardly by the pressure of its spring 17, thereby engaging the detent 14 in the proper notch of the toothed sector 16. When the detent 14 has seated in the selected notch (limiting the upward movement of the latch handle 11), the lock 20, under pressure of its spring 23, automatically moves rearward at its upper end to bring the shoulder 26 into locking engagement with the projection 27, thereby preventing the retraction of the holding detent. In other words, when the shoulder of the lock 20 is in locking engagement with the latch handle 11, it is impossible for the adjustment of the ejector to be changed unless the safety lock is first released, and held released,

by an upward pressure exerted on the grip portion 20^a, followed by a downward pressure on the handle 11. It will be understood, of course, that in making a deliberate change 5 of adjustment of the ejector, the operator has merely to grasp the handle 9^a in the usual way, the pressure exerted on the latch handle 11 and the grip portion 20^a taking place as if those parts formed part of the lever 10 handle itself, as in a sense they do.

Having thus described my invention, what I claim is:

1. In a typographical machine equipped with an ejector variable in width, the combination 15 of a hand lever for changing the width of said ejector and presenting an operating handle, a spring-pressed latch handle pivotally mounted on the lever handle and having a locking detent adapted to hold 20 the lever handle in its set position, and a spring-pressed safety lock also pivoted on the lever handle and normally held in engagement with the latch handle, the safety lock and the latch handle being arranged to be 25 gripped and successively disengaged by the attendant in operating the hand lever.

2. A combination as in claim 1, wherein the safety lock is formed at one end with a shoulder to engage the outer end of the latch 30 handle and at its opposite end with a grip portion extending substantially parallel with the lever handle.

3. A combination as in claim 1, characterized 35 by the fact that the lever handle is bifurcated at its outer end and that the pivoted safety lock is mounted to rock in said bifurcation.

4. In a typographical machine equipped 40 with an ejector variable in width, the combination of a hand lever for changing the width of said ejector and presenting an operating handle, a latch handle pivoted on the upper side of the lever handle and having a locking detent adapted to hold the lever handle 45 in its set position, a compression spring arranged between the lever handle and the latch handle and pressing upwardly on the latter to maintain the locking detent in active position, a safety latch pivoted on the lever handle at its outer end and comprising an upper 50 detent portion arranged to engage the latch handle at its outer end and a lower grip portion arranged on the underside of the lever handle, and a compression spring arranged 55 between the lever handle and the safety lock grip portion and pressing downwardly on the latter to maintain the upper detent portion in active position, substantially as shown and described.

60 In testimony whereof, this specification has been duly signed by:

JOHN H. HILPMAN.
